BINDER

Clarence D. Trussell, Poughkeepsie, N. Y., assignor to Trussell Manufacturing Company, Poughkeepsie, N. Y., a corporation of New York

Application January 21, 1938, Serial No. 186,022

12 Claims. (Cl. 281—19)

1 The invention herein disclosed relates to binders of the type in which rings binding the leaves together enter in correspondingly placed notches in an arched support and are held in that relation by a pin or key extending through the arch and through the rings disposed in the notches of the arch.

10 The purpose of the present invention is to improve such constructions, particularly in the matters of facilitating the entry of the securing pin, enabling the use of a lighter and less expensive pin and effecting reliable and at the same time releasable holding and positioning of the pin in the arched supporting structure.

15 Other objects and the novel features of construction, combinations and relations of parts by which all objects of the invention are attained are set forth and will appear in the course of the following specification.

20 The drawing accompanying and forming part of the specification illustrates a present preferred embodiment of the invention. Structure however may be varied from this disclosure, all within the true intent of the invention as will be apparent from the following specification and claims.

25 Fig. 1 is a broken plan view of a multiple section binder incorporating features of the invention.

Figs. 2 and 3 are enlarged broken sectional details on substantially the planes of lines 2—2 and 3—3 of Fig. 1.

30 Fig. 4 is a broken enlarged plan view of the lower portion of the support shown in Fig. 1.

Fig. 5 is an enlarged and broken longitudinal sectional view as on line 5—5 of Fig. 1.

35 Fig. 6 is a detail view of one of the securing pins.

In the illustration, the supporting structure comprises a book back 7, having integrally attached covers 8, 9, and having secured to it as by rivets 10, a back plate 11. On this back plate there is secured a plate 12, having upstruck arches 13, notched at 14, to receive the binder rings 15.

40 The binder rings are shown as of the "Wire-O" design consisting of double strand rings formed from a continuous length of wire bent in zig-zag fashion to provide these double strand rings connected in spaced parallel relation.

45 The structure shown is a three section binder and consequently the plate 12 is formed up with three parallel archways 13, each notched to receive the rings of one binder section. There may be more or fewer sections however, for while the invention is of particular advantage for multiple section large thick books, special features of the invention may be found equally desirable for smaller single section binders.

50 The pins for retaining the binder rings between the loops formed by the notched arches differ from those usually employed in that they consist each of a relatively light and flexible round wire 16, as distinguished from a heavy, stiff and practically

rigid rod or flat bar such as heretofore employed. This lighter and more flexible wire will yield and bend with the bending of the binder rings and support in the normal handling of the book and to compensate for variations in dimension of parts 5 incidental to manufacture. This smaller diameter wire permits of the loops or arches being made smaller and lighter material to be used for the supporting plate 12.

To give the key wires a definite frictional grip 10 with the arches and the binder rings they may be bent as indicated at 17, Figs. 5 and 6, to offset one portion with respect to an adjoining portion, so that in being entered in the archways they will be to some extent "straightened" and be put under 15 tension to a degree dependent on the extent of such straightening.

To facilitate the entry of the flexible and more or less flimsy wire into the end of the notched archway, a special guide is provided consisting in 20 the present disclosure of a lug 18, partially detached and struck up from the body of plate 12, and having in its upper surface a tapered channel 19, leading directly into the upper portion of the end loop of the archway. This enables the wire to 25 be easily entered by simply resting the end of the wire in the channel 19, and which as thrust is applied, will center and direct the wire straight on into the end of the archway. This guide also by holding the wire up in the top of the arch tends to 30 bind it against the top and thus frictionally retain it in place. If the wire is bent, as indicated, this guide also will exert a straightening tendency and hence further operate as a retainer for the wire.

Some convenient form of handle is preferably 35 provided on the wire. For example, the end of the wire may simply be bent at approximately a right angle to provide an integral form of handle such as indicated at the right at 20, in Fig. 1. In another embodiment, a small flat finger plate 21, 40 is swedged on the end of the wire at 22. In this form of construction, the bottom edge 23, of the finger piece slides over the surface of the back plate 11, Fig. 5, to hold the wire up in the top of the arch and to frictionally retain the wire non- 45 rotatably in position in the supporting arch. In Fig. 5, the binder rings are omitted for better illustration of the deformed retaining pin or wire. The binder loops when in position however would have the effect of tending to straighten the wire so 50 that in actual use, the wire would not remain bent to the extent indicated and would in fact be restored practically to straight condition, held so by the cooperative action of the retainer loops and the binder loops in their relatively overlapping 55 relation.

The pin guiding steps 18, at the entrances to the retainer arches need project only a slight distance. Preferably however they will project somewhat below or beyond the end of the bound 60

sheets, after the manner indicated in Fig. 4, so that the ends of the retainer arches will be found by the binder wires even though practically hidden by the bound sheets 16a.

5 The plate 12 carrying the retainer arches and entrance guides may be fastened in position in various ways, as for instance, by means of retainer lugs 24, struck up from the back plate 11, through openings 25, and bent over the face of plate 12, as in Figs. 2 and 4.

10 The structure disclosed is simple and relatively inexpensive. The bent retainer wires firmly hold the binder units in the supporting structure, yet permit any unit to be selected and quickly removed by simply withdrawing the binder wire holding that unit. Similarly, any bound group of sheets may be quickly secured in the holder by simply placing it with the binder rings entered in the notches and then slipping the point of the 15 wire over the guide and into the end of the retainer arch. As indicated in Fig. 5, the pin guides 18 at the entrances to the retainer loops may, by reason of engagement of the finger lugs therewith, limit the extent to which the pins can be 20 inserted in the holder loops. The finger pieces 21 of the retainer wires when fully in position are held by the back plate 11, against turning and in definite upright position as shown at the 25 left in Fig. 1 and Fig. 5, where they are readily seen and can be conveniently grasped.

30 What is claimed is:

1. In a binder in which leaves are held by binder rings entered in notches in an arched support and in which said rings are retained in such 35 relation by a pin passing beneath the support and above those portions of the rings entered in said notches, a guide at the entrance to said arched support for directing the end of the pin into the arch of said support.

40 2. In a binder in which leaves are held by binder rings entered in notches in an arched support and in which said rings are retained in such relation by a pin passing beneath the support and above those portions of the rings entered in 45 said notches, a guide at the entrance to said arched support for directing the end of the pin into the arch of said support, said guide comprising a step provided with a convergent guide channel opening directly into the end of the 50 arched support.

55 3. In a binder in which leaves are held by binder rings entered in notches in an arched support and in which said rings are retained in such relation by a pin passing beneath the support and above those portions of the rings entered in said 60 notches, a guide at the entrance to said arched support for directing the end of the pin into the arch of said support and said pin consisting of a flexible wire having one or more bends therein.

65 4. In a binder in which leaves are held by binder rings entered in notches in an arched support and in which said rings are retained in such relation by a pin passing beneath the support and above those portions of the rings entered in said notches, a guide at the entrance to said arched support for directing the end of the pin into the arch of said support and said pin having a finger grip engageable as a stop against said pin guide.

70 5. A binder comprising a supporting plate having an arched portion notched to receive binder rings and said plate having a pin guiding lug struck up therefrom at the entrance to one end of said notched arched portion.

75 6. In a binder of the character disclosed, a supporting plate having an arched portion

notched to receive binder rings and said plate having an upstruck lug at the entrance to one end of said arched portion, said lug having a pin guiding channel indented therein.

7. In a binder of the character disclosed, a supporting plate having an arched portion notched to receive binder rings and said plate having an upstruck lug at the entrance to one end of said arched portion, said lug having a pin guiding channel indented therein, said channel being tapered convergently toward said entrance.

10 8. A binder comprising a support, spaced loops carried by said support, binder rings entered in the spaces between said loops, a retaining pin extending beneath said loops and above portions 15 of the binder rings entered in the spaces between the loops, a guide at the entrance end of said loops for directing the end of said retainer pin thereinto, a finger piece on the end of said retaining pin and means engageable by said finger piece for holding said finger piece in non-rotatable relation.

15 9. In a binder in which leaves are held by binder rings entered in notches in an arched support and in which said rings are retained in such 20 relation by a pin passing beneath the support and above those portions of the rings entered in said notches, a guide at the entrance to said arched support having a guide channel for receiving the end of the pin and opening directly 25 into the adjoining end of the arched support.

25 10. In a binder in which leaves are held by binder rings entered in notches in an arched support and in which said rings are retained in such 30 relation by a pin passing beneath the support and above those portions of the rings entered in said notches, a guide at the entrance to said arched support having a guide channel for receiving the end of the pin and opening directly 35 into the adjoining end of the arched support, said guide being yielding in character and tensioned toward the top of the arch to thereby apply a holding force to the protruding portion of a pin entered in said arched support and overlying said guide.

40 11. In a binder in which leaves are held by binder rings entered in notches in an arched support and in which said rings are retained in such 45 relation by a pin passing beneath the support and above those portions of the rings entered in said notches, a guide at the entrance to said arched support for directing the end of the pin into the arch of said support and said guide being yieldable and tensioned toward the top of the arch to thereby apply a yielding holding force 50 to the protruding portion of a retaining pin entered over said guide into the arch of said support.

55 12. A sectional binder comprising a support, parallel rows of spaced arches on said support, 60 binder sections having rings correspondingly spaced to enter in the spaces between the arches in said rows, a retaining pin for each binder section extending beneath the arches and above portions 65 of the binder rings entered therebetween, guides at the entrances to the rows of arches for directing said retaining pins thereinto, said retaining pins having angularly offset finger pieces at the outer ends of the same and means at said guides engaging with said finger pieces in the 70 fully seated positions of the pins for holding said finger pieces in definitely positioned relation readily accessible for effecting release of selected binder sections.
